UNITED STATES PATENT OFFICE.

HENRY HESS, OF PHILADELPHIA, PENNSYLVANIA.

PENCIL.

1,358,548.

Specification of Letters Patent. Patented Nov. 9, 1920.

Application filed July 9, 1917. Serial No. 179,357.

To all whom it may concern:

Be it known that I, HENRY HESS, a citizen of the United States, residing at Philadelphia, in the county of Philadelphia and

5 State of Pennsylvania, have invented certain new and useful Improvements in Pencils, of which the following is a specification, reference being had therein to the accompanying drawing.

10 This invention relates to magazine pencils of the type in which the lead is advanced or fed forwardly and projected from the end of the pencil to form a writing or marking point, the aim of the invention being to produce a pencil of extremely simple construction, made up of few parts, in which very slender leads may be employed without danger of breakage, in which the feeding of the lead to present a new point may be effected 15 positively, conveniently and expeditiously, and in which the lead will be firmly and solidly held without liability of looseness or escape.

With these and other objects in view my 20 invention consists in the improved form and construction of the parts fully described in the specification to follow and the novel features of which will be set forth in the appended claims.

30 In the accompanying drawings:

Figure 1 is a longitudinal section through a pencil constructed in accordance with my invention.

Fig. 2 is a cross section through the same 35 on the line 2—2.

Fig. 3 is a side elevation of the barrel of the pencil disconnected from the other parts.

Fig. 4 is a cross section on the line 4—4 of 40 Fig. 3.

Fig. 5 is a side elevation of the feeding plunger rod removed.

Referring to the drawings:

In its essential features, my improved 45 pencil comprises a barrel 1 to receive and hold the lead 2, a feeding plunger 3 movable in the barrel in engagement with the lead to feed the same, and a plunger actuating member 4 sustained by the barrel and 50 movable longitudinally thereof in engagement with the plunger to advance the same.

The barrel is cylindrical in form with a bore 5 extending longitudinally therethrough from end to end, which bore is of 55 uniform cross-sectional area throughout its extent, and is of a diameter corresponding

to the diameter of the lead so that the lead will be frictionally held throughout its length. As a result the lead will be solidly held and not liable to break when pressure is exerted on the projecting writing point, as would be apt to occur if the lead were gripped at one point only in its length as is the case with many forms of magazine pencils. The forward end of the barrel is 60 formed with a longitudinal slit 6 extending entirely through the same from side to side and some distance toward the rear, whereby the lead will be held with a spring-gripping action sufficiently tight to present a solid 65 writing point free from looseness but not too tight to interfere with the proper feed of the lead by the feeding plunger. In the present instance the bore of the barrel is of a diameter to accommodate a lead of slender size so that the necessity of re-sharpening the lead to present a point sufficiently fine for writing is avoided.

70 The feeding plunger 3 is in the form of a cylindrical rod or section of wire of a 75 diameter to fit snugly in the bore and is of a length to extend at its rear end beyond the rear end of the barrel as shown in Fig. 1. In this position the forward end of the plunger engages the rear end of the lead, 80 so that when the plunger is advanced by the means now to be described, the lead will be positively pushed before it and its forward end projected beyond the end of the barrel.

85 The plunger actuating member is in the 90 form of a hollow sleeve closed at its rear end by a head or end wall 8. The sleeve surrounds the rear portion of the barrel and the projecting end of the plunger, and is threaded interiorly as at 9 to engage external screw threads 10 on the rear end of the barrel, so that by turning the sleeve on the barrel in the proper direction, it will telescope thereon and advance longitudinally thereof. The rear end of the plunger rod 100 being engaged by the end wall of the sleeve, the rod will in this action be forced forwardly by the sleeve and engaging the lead the latter will be fed.

105 The construction described is very simple in form and comprises but three parts, viz., the barrel, the plunger and the plunger actuating member. The device is therefore free from complications and not liable to disarrangement, and is consequently economical to produce. The feeding action is effective, reliable and positive, and may be 110

conveniently effected by gripping the sleeve in the palm of the hand and turning the barrel with the thumb and finger of the same hand.

6 In order to give the pencil a finished appearance and produce a comfortable grip for the fingers, in writing I propose to provide a casing 11 to surround the barrel. The casing is of hollow cylindrical form and is attached at its forward end to the forward end of the barrel, from which point it extends rearwardly around the barrel and surrounds at its rear end the forward end of the sleeve 4, the sleeve 4 in its movements sliding between the barrel and casing. The casing thus fixedly connected with the barrel forms in effect a continuation of the same which surrounds the barrel, but it will be understood that the casing need not be constructed as a separate part and attached to the barrel, but the two may be made in a single integral piece, the function of the casing being to give the pencil a substantially uniform size throughout its extent, and afford a more comfortable hold to the fingers than would result if the comparatively slender barrel were exposed.

In the foregoing description and accompanying drawings I have set forth my invention in the particular form which I prefer to adopt and which in practice has been found to answer to a satisfactory degree the ends to be attained. It will be manifest, however, that the details may be variously changed and modified without departing from the limits of my invention, and further it will be understood that the invention is not limited to any particular form or construction of the parts except in so far as such limitations are specified in the claims.

Having thus described my invention, what I claim is:

1. In a pencil, the combination of a barrel provided with a longitudinal bore to receive and hold a lead, a plunger movable in

said bore with its forward end in engagement with the lead to feed the same, and with its rear end projecting beyond the rear end of the barrel, and a rotary plunger actuating device mounted on the barrel and positively and directly engaging but wholly disconnected from the rear end of the plunger and rotatable relatively to the same, said device provided with means whereby it is adapted in its rotation to positively move longitudinally along the barrel and advance the plunger without turning it.

2. In a pencil, the combination of a barrel threaded exteriorly at its rear end and provided with a bore to receive and hold a lead, a plunger rod slidable without rotation in said bore with its forward end in engagement with the lead and with its rear end projecting beyond the rear end of the barrel, and a plunger actuating sleeve surrounding the barrel and projecting beyond the rear end of the plunger rod and threaded interiorly to screw on the barrel, said sleeve positively and directly engaging but being wholly disconnected from the rear end of the plunger and being rotatable on the barrel relatively to the plunger; whereby in the rotation of the sleeve, the lead will be positively advanced longitudinally in the barrel without turning.

3. The combination of a barrel provided with a bore to receive and hold a lead, a plunger rod movable in the bore in engagement with the lead to feed the same, a plunger actuating member consisting of a sleeve surrounding the barrel in engagement with the plunger and movable longitudinally of the barrel, and a cylindrical casing fixed at its forward end to the forward end of the barrel and surrounding the same and extending rearwardly and loosely surrounding the sleeve.

In testimony whereof, I have affixed my signature hereto.

HENRY HESS.
